UNITED STATES PATENT OFFICE.

EMILE A. FOURNEAUX, OF NEW YORK, N. Y., ASSIGNOR TO HERMAN A. METZ, OF NEW YORK, N. Y.

FORMALDEHYDE HYDROSULFITE AND PROCESS OF MAKING SAME.

No. 812,124.

Specification of Letters Patent.

Patented Feb. 6, 1906.

Application filed March 30, 1905. Serial No. 252,867.

To all whom it may concern:

Be it known that I, EMILE A. FOURNEAUX, a citizen of the United States, residing at New York, in the county of New York and State of New York, have invented certain new and useful Improvements in Formaldehyde Compounds of Bihydrosulfites and Processes of Making Same, of which the following is a specification.

10 In the United States Patent No. 769,593 Louis Descamps describes and claims the manufacture of certain compounds obtained by the action of aldehydes on hydrosulfites, and more particularly the body obtained by the action of formaldehyde on sodium hydrosulfite, to which he assigns the formula:

20 On December 1, 1904, Messrs. Luc. Baumann, G. Thesmar, and Jos. Frossard published a paper in the *Revue Generale des Matieres Colorantes* in which they prove that the 25 compound described by Mr. Descamps is not a chemical individual, but merely a mechanical mixture in more or less molecular proportions of two bodies: the formaldehyde compound of sodium bisulfite,

and the body termed by them the "formaldehyde compound of sodium bihydrosulfite," $\text{NaHSO}_2\text{CH}_2\text{O} + 2\text{H}_2\text{O}$, which result from 35 Bernthsen's sodium hydrosulfite by the following reaction:

45 Of these two bodies, which constitute the material commercially known as "hyraldite" or "hydrosulfite" NF, the formaldehyde sodium bihydrosulfite is the active constituent, whereas the formaldehyde compound of sodium bisulfite is merely an unavoidable and undesirable impurity.

The method described by Messrs. Baumann, Thesmar, and Frossard for producing the formaldehyde compound of sodium bihydrosulfite is so lengthy and onerous as to be of little or no commercial value.

If it were possible economically to manufacture the active constituent of hydrosulfite

1 NF or hyraldite in a pure state, free from the formaldehyde compound of sodium bisulfite, 55 this would constitute a very material improvement and progress over the present methods, because it possesses almost twice the reducing power of the above-named hydrosulfites and is materially more stable, 60 owing to its purity.

To avoid confusion of terms, the salts corresponding to the general formula $\text{M}_6\text{S}_2\text{O}_4$ (Mé indicating any univalent metal) heretofore considered as derived from the hypothetical hydrosulfurous acid of Bernthsen; $\text{H}_2\text{S}_2\text{O}_4$, are herein termed "hydrosulfites" in accordance with common usage, and the salts derived from the hypothetical hydrosulfurous acid of Schuetzenberger, H_2SO_4 , are 70 hereinafter referred to as "hydrosulfites," (S).

I have found a method by which formaldehyde compounds of hydrosulfites (S) can be prepared economically and in a state of great purity and have also discovered a new and heretofore unknown basic zinc formaldehyde hydrosulfite (S) which is instrumental in carrying out my invention. This salt separates quantitatively as a white crystalline precipitate upon addition of the required amount of 80 a suitable alkaline salt, preferably sodium carbonate, to a solution of zinc hydrosulfite which has been treated with formaldehyde until it ceases to reduce a solution of indigo sulfonic acid at ordinary temperature. This 85 new basic zinc-salt is characterized by its great reducing power, one part reducing in the neighborhood of one and one-half parts of pure indigo in the form of indigo sulfonic acid and by its great stability, as it can be 90 dried on the water-bath in the open air without decomposing, which is entirely unprecedented in hydrosulfite compounds and quite unexpected. The actual composition of this compound has not yet been ascertained with 95 absolute exactness, but it is believed to correspond to the formula: $\text{ZnSO}_2\text{CH}_2\text{O} \cdot \text{H}_2\text{O}$ and to be formed by the following reaction:

By treating this zinc-salt with a solution of sodium carbonate the corresponding sodium salt is formed quantitatively and can be separated from its solution by evaporation. It appears to be identical with the

product, $\text{NaHSO}_2\text{CH}_2\text{O} + 2\text{H}_2\text{O}$, described by Messrs. Baumann, Thesmar, and Frossard.

If the basic zinc-salt is treated with an acid, the free acid is liberated and can be used for the preparation of other salts by the well-known methods. This free acid is also remarkably stable. Its solution decomposes only when heated for some time, when sulfuric acid is given off and a yellow oil separates, which becomes crystalline on cooling.

The basic zinc-salt may be prepared by various methods, a satisfactory procedure being as follows: One hundred and twenty parts zinc-dust are pasted up with three hundred parts boiling water and added to nine hundred parts cold water in a lead-lined kettle provided with a stirrer and the amount of sulfuric acid introduced, which is just sufficient to dissolve the total amount of zinc—approximately two hundred parts. The temperature during this whole process should not exceed 45° centigrade. The resulting solution of zinc hydrosulfite is then cooled to a temperature not exceeding 30° centigrade, filtered to separate it from zinc sulfite and other impurities, and formaldehyde added until the product no longer reduces a solution of indigo sulfonic acid at ordinary temperature. The amount of formaldehyde required is about two hundred and fifty parts. Then add a highly-concentrated solution of sodium carbonate until the basic zinc-salt is completely precipitated and the mother-liquors, which should still be slightly acid to litmus no longer or but very slightly, reduce indigo sulfonic acid at a temperature exceeding 45° centigrade. The amount of sodium carbonate required is about eighty parts. The white crystalline precipitate is then filtered and washed in the usual way and dried. It can be applied as such for reducing and discharging purposes or for the manufacture of other formaldehyde hydrosulfites (S) in the manner above described.

The formation of this zinc-salt appears to be a secondary reaction. There is at first precipitation of a heavy flocculent white body, which soon decomposes, giving off car-

bon dioxid and separating the crystalline basic zinc-salt.

50

The basic zinc-salt may be prepared by other methods—as, for instance, by reaction of zinc-dust and a suitable acid on sodium bisulfite formaldehyde under suitable conditions, as described in my copending application, Serial No. 259,469, filed May 8, 1905.

55

I claim—

1. The process of making basic zinc formaldehyde hydrosulfite (S) which consists in reacting with a suitable alkali compound upon a solution of zinc hydrosulfite treated with formaldehyde, substantially as described.

60

2. As a new article of manufacture, basic zinc formaldehyde hydrosulfite (S) occurring as a white crystalline precipitate, capable of being dried on the water-bath in the open air without decomposing, and one part capable of reducing about one and one-half parts of pure indigo in the form of indigo sulfonic acid, substantially as described.

65

3. The process of making alkali formaldehyde hydrosulfite (S) which consists in reacting with a suitable alkali compound upon the basic zinc formaldehyde hydrosulfite (S), substantially as described.

70

4. The process of making sodium formaldehyde hydrosulfite (S) which consists in reacting with sodium carbonate upon basic zinc formaldehyde hydrosulfite (S), substantially as described.

75

5. The process which consists in reacting with a suitable alkali compound upon a solution of zinc hydrosulfite treated with formaldehyde, thereby forming basic zinc formaldehyde hydrosulfite (S), and then reacting with a suitable alkali compound upon said basic zinc formaldehyde hydrosulfite (S) to form alkali formaldehyde hydrosulfite (S), substantially as described.

80

In testimony whereof I affix my signature in presence of two witnesses.

EMILE A. FOURNEAUX.
